PRINTING MACHINE

Eugen Buhler, Binghamton, N. Y., assignor to International Business Machines Corporation, New York, N. Y., a corporation of New York

Application April 27, 1938, Serial No. 204,525

5 Claims. (Cl. 101—96)

This invention relates to a printing machine and more particularly to a printing machine controlled by perforated cards of the well known Hollerith type.

One of the objects of the present invention is to provide a machine for printing data on a card to interpret a plurality of perforations appearing in said card.

Another object is to provide a device for printing indicia on a perforated card, interpreting perforations in said card, and in which the perforations in the card control the printing of indicia on the card.

Still another object is to provide a machine for printing data on a card to interpret perforations in said card in which cards are fed to printing position by a continuously operating printing mechanism and in which the card is stopped in printing position by a device disposed in the path of the movement of said card and in which a deflecting device deflects the card over the stopping device to cause it to resume its feed from printing position.

A still further object of the invention is to provide a printing machine for printing data on a card controlled by perforations therein and in which provision is made to selectively control the position on the card at which said data may be printed.

Further objects of the instant invention reside in the novel feature of construction or operation or novel combination of parts present in the embodiment of the invention described and shown in the accompanying drawings whether within or without the scope of the appended claims and irrespective of other specific statements as to the scope of the invention contained herein.

In the drawings:

Fig. 1 shows an elevation of the mechanism.

Fig. 2 shows a detailed view of the storage mechanism.

Fig. 3 shows a detailed view of the deflector mechanism and ejector mechanism.

Fig. 4 shows a section of a card illustrating the different positions on the card in which printing may be effected.

Fig. 5 shows a diagrammatic illustration of the gear trains and driving mechanism.

Fig. 6 is a section taken on lines 6—6 of Fig. 2.

Fig. 7 shows the coding for the different type characters.

Fig. 8 is a wiring diagram of the machine.

In order to clearly understand the timing of the different elements of the machine, the driving mechanism and its associated gear trains as

shown in Fig. 5 will first be explained. The shaft 10 is the drive shaft which may be driven directly from a prime mover by any suitable method. The general practice in accounting machines of this type is a belt and pulley connection to an electric motor. To the drive shaft are fixed gears 11, 12, and 13. Gear 13 meshes with gears 14 and 15 and through gear 14 drives gears 16, 17, 18, 19, and 20 which are connected in train. The gear 11 meshes with gear 21 with a 4 to 1 reduction so that the gear 21 makes one revolution for four revolutions of the drive shaft 10. The ratio of gearing to the feeding mechanism and machine cycle operation is such that gear 21 makes one revolution per machine cycle. Fixed to gear 21 is a gear 22 which meshes with a gear 23 which in turn drives gears 24, 25, and 26. The gears 16, 18, 20 and 26 carry feed rollers on their respective shafts and the gear 25 carries a contact roll 27 (Fig. 8). The feed rollers on the shafts of the gears 16, 18 and 20 rotate at a higher speed than those on the shafts 25, 24, and 26 so that they move away from printing position more rapidly than they approach it.

Gear 21 drives gears 28 and 29 in train. The shaft 30 represents one end of a split shaft and 30a the other end, both shafts being in axial alignment. The gears 28 and 31 are fixed to the shaft 30a. Gear 31 meshes with gear 32 with a 2 to 1 reduction so that gear 32 makes one-half a revolution per machine cycle. Gear 32 is fixed to a counter shaft 33 to which is also fixed a gear 34 meshing with gear 35 with a 1 to 1 ratio, and gear 35 is fixed to the shaft 30. It will be seen therefore that one of the split shafts makes one revolution per machine cycle and the other makes one-half revolution per machine cycle. These shafts are cam shafts on which various cams for operating contacts are mounted and will hereinafter be designated as the one cycle cam shaft and the half cycle cam shaft. The gear trains above described are located on the right hand side of the machine as one faces the card magazine or picker mechanism to be described later.

The gear 21 is fixed to a shaft 36 which extends across to the left hand side of the machine and is journaled in the supporting frames. A gear 37 is fixed to the left end of said shaft and meshes with a gear 38 which in turn drives gears 39 and 40. The gear ratio is such that gears 39 and 40 make one-half revolution per machine cycle. Gear 39 is fixed to its supporting shaft as is also a cam 41. Gear 40 is fixed to its supporting shaft as is also a box cam 42.

Turning now to Fig. 1, a hopper 43 is provided in which a stack of cards 44 may be placed. These cards are perforated record cards such as is well known and widely used in the Hollerith type of accounting and sorting machines. The cards are fed one by one from the bottom of a stack by means of a picker 45 which is oscillated back and forth once per machine cycle. The cards are fed between feed rollers 46, through the card guide 47, between the contact roll 48 and sensing brushes 49, between the printing hammer 50 and the type wheel 51 and against a gate 52 (Figs. 1 and 3) which projects slightly into the card guide 54. Feeding and conveying mechanism of this type is old and well known in the art and is fully disclosed in the United States patent to E. A. Ford, No. 1,684,389, dated September 18, 1928. The picker 45 is oscillated back and forth once each cycle by means of an arm 56 fixed to a shaft 57 which is journaled for rotation in the frame structure of the machine. An arm 58 is fixed to another end of the shaft and pivotally connected to a connecting rod 59 the opposite end of which is pivotally connected by a stud to the gear 29 which makes one revolution per cycle as previously explained. It will be seen therefore that the rotation of the gear 29 transmitted through the foregoing linkage will cause the picker 45 to oscillate once each machine cycle.

The type wheel 51 is the same as that shown in my United States Patent No. 2,036,016, dated March 31, 1936, with the exception that there are a few more characters added as will be seen from the code designation shown in Fig. 7. In this figure the first two columns represent the index points that must be perforated to effect printing of the corresponding character appearing in the third or left hand column.

The conveying rollers feed the cards frictionally, one of said rollers being journaled in a fixed bearing and the other cooperating roller being on the end of a spring-pressed bell crank as indicated by the reference character 60 in Fig. 1, so that when a card is halted against the gate 52 the feed rollers continue to rotate frictionally against the face of the card. The location of the feed rollers with respect to the cards is the same as shown in United States Patent 1,684,389 previously mentioned in which the rollers bear on the end extremities of the cards, whereas the gate 52 projects into the path of the card at a central point between the rollers.

The gate 52 is fixed to an angular support 61 (Fig. 3) which is mounted to a supporting bracket 62 slidably mounted on the side support of the machine. The bracket 62 has mounted thereon a magnet supporting structure 63 to which is mounted a magnet 64. The magnet 64 has a hollow core with a solenoid plunger extending therein and pivotally fastened at one end to a pin 65 in one arm of a bell crank 66 which is pivotally mounted to the bracket 62 at 67. The other arm of the bell crank terminates in a ball-shaped structure 68 which engages an aperture in a bail 69 which is located adjacent and parallel to the gate 52 and is slideable up and down so that the top edge of the bail when in its raised position will project slightly above the upper edge of the gate 52, and will be below the upper edge 52 when in its lowered position as shown in Fig. 3. At 70 a spring normally biases the bell crank 66 in a clockwise direction, therefore normally holding

the bail 69 at its lowered position. When the magnet 64 is energized, its solenoid plunger is pulled to the left as viewed in Fig. 3 turning the bell crank 66 to raise the bail 69.

5 Fixed to the side frame of the machine is strip 71 having a number of locating holes thereon which may be engaged by a bolt 72 (Fig. 1) slidably mounted in the supporting structure 63. A manual 73 is fixed to the bolt 10 to slide it in and out of engagement with the locating holes 71.

Three of these locating holes 71a, 71b, and 71c are shown in Fig. 1, the bolt 72 is engaged with another one, and two others spaced the same 15 distance apart, as 71a and 71b, are hidden from view behind the manual 73. The purpose of this movable gate assembly is to locate the card relative to the type and printing hammer to properly locate the printing on the card. In 20 Fig. 4 the various positions for printing on the card are shown. As the lower edge of the card is the leading edge while passing through the machine, it may be readily understood that the top line registers over the printing hammer 50 when the gate is positioned with the bolt 72 25 engaging the extreme left hand hole 71a as viewed in Fig. 1. It will be noted that the printing is located between the index point locations, only one column of which is shown in 30 Fig. 4. The horizontal rows of index points run parallel to the long edges of the cards. In this way, perforations throughout the card will not obliterate the printing. Such a type of card is shown in the patent to C. D. Lake, No. 35 1,772,492, dated August 12, 1930.

The cards are fed along the guideway 47 and it will be seen in Fig. 3 that the lower guide of the guideway is provided with a camber 75. The purpose of this camber is to deflect the following 40 edge of the card upwardly when the leading edge is against the gate 52, and the motion of the card is halted for receiving the printed record. It will be understood that the card feeding mechanism is not interrupted at this time so that 45 the following card continues to approach the now arrested card. By deflecting the following edge of the arrested card upwardly, the leading edge of the following card will slide underneath the arrested card.

50 As previously stated, the card is fed along the guideways until the leading edge strikes the gate 52 at which time its feeding movement is arrested to place the card in proper printing position; printing is then effected in a manner 55 to be described later, after which the magnet 64 becomes energized, causing the bail 69 to be raised, thus lifting the leading edge of the card over the top of the gate.

The card continues to be fed and is soon 60 gripped by the rollers driven by the gear 16 which rapidly takes the card away to clear the path for the following card to be positioned for printing. The cards are fed out of the machine and dropped into the pocket 76.

65 When the gate 52 and its associated assembly is moved so that the bolt 72 engages either the hole 71b or 71c, the following edge of the card will have cleared the camber 75 so that it will not be held turned upwardly when the card is halted by the gate. The leading edge of the following card, however, would be passing over the camber and so have a tendency to ride along the top of the guideway and so pass on top of the foregoing card. To direct this leading edge under the following edge of the foregoing card a bail 80 is

provided fixed to an arm 81 which in turn is fixed to a rotatably mounted shaft 82. Also fixed to the shaft 82 is a bell crank 83 which is biased in a counterclockwise direction by a spring 84 and which is held against the end of an armature 85 pivoted at 86 and biased in a clockwise direction by a spring 87. The other arm of the bell crank carries a cam roller 88 which cooperates with a cam 89. A magnet 90 is associated with the armature 85 so that when energized the armature 85 is swung to the right (Fig. 3) removing the end of the armature from the path of the arm of the bell crank. A latch member pivotally mounted at 91 has one end 92 engaged with the armature and another end 93 disposed under the bell crank arm. When the armature moves to the right the latch member is rotated clockwise so that the end 93 kicks the bell crank 83 counterclockwise. This operation depresses the bail 80 to press the leading edge of the card, under it at the time, downwardly to pass under the following edge of the preceding card. This operation only occurs when the gate assembly is located with the bolt engaging holes 71b and 71c at which positions a contact fixed to the slideable assembly engages a contact fixed to the machine to throw the magnet 90 into circuit with cam operated contacts driven in cycle with the machine to cause the operation of the bail 80 downwardly when the leading edge of a card is being fed under it. This operation will be explained later in connection with the circuits. When the bell crank 83 has been released by the armature to rock counterclockwise the roller 88 engages the cam 89 which restores it prior to the leading edge of the next card being fed under the bail 80. The cam 89 has a high point 94 which rocks the bell crank 83 clockwise. The end of the arm, when so rocked, strikes the end 93 of the latch member rocking it counterclockwise and positively kicking the armature 85 to the left (Fig. 3) and into the path of the arm of the restored bell crank 83 to hold it there until the next time the magnet 90 is energized. The magnet 90 is only momentarily energized and is de-energized when this restoring action is effected.

When the slideable gate assembly is positioned with its bolt engaging the last hole 71a the card is located to receive a printed record at the top edge of the card as shown at 95 (Fig. 4). This edge, when arrested, is so far in advance of the following card that it is released and fed out of the way before the following card can interfere with it.

Printing mechanism

The type wheel 51 is provided with fixed type around its periphery and is fixed to the shaft 55. A gear 11 (Fig. 5) also fixed to said shaft is driven by the gear 12 on the drive shaft 10. The ratio of the gearing is such that the type characters pass the printing hammer 50 in synchronism with the passing of the teeth on ratchet wheel 78 past a fixed point. The ratchet wheel 78 is fixed to the shaft 10. A casing 79 surrounds the type wheel with an opening at the bottom adjacent the type hammer and an ink ribbon (not shown) passes around the casing and terminates in two spools (not shown) located above the casing. Such an arrangement of the ribbon and spools is fully shown in Fig. 2 of my United States Patent No. 2,036,016, previously referred to.

A printing operation is effected in the following manner: A member 96 pivotally mounted at 97 is rocked in a counterclockwise direction by 75

means and in a manner to be explained later. The member 96 has an extension 98 which is connected by means of a spring 99 to the printing hammer 50 pivotally mounted at 100, thus biasing member 96 clockwise and member 50 counterclockwise. The member 96 is bifurcated at its upper end and provided with two arms 101 and 102. The arm 101 is provided with a shoulder on which a projection 103 integral with the hammer 50 normally rests. The arm 102 is provided with a camming surface which cooperates with a camming surface on the arm 102. The printing hammer 50 has a projection 104 adjacent to the ratchet wheel 78 and adapted to be moved into the path of the teeth of said ratchet wheel. When the member 96 is kicked in a counterclockwise direction, the shoulder in arm 101 is removed from under the projection 104 and the spring 99 pulls the hammer counterclockwise which moves the projection into the path of the teeth of the rapidly rotating ratchet wheel 78. The teeth strike the projection 104 firing the hammer 50 against the type wheel. As the hammer 50 is projected clockwise, the camming surface on the projection 103 strikes the camming surface on the arm 102 to move the member 96 clockwise to restore it so that upon the rebound of the hammer 50 the projection will rest on the shoulder of the arm 101. 30 The movement of the member 96 in a counterclockwise direction to cause the printing operation just described is effected in the following manner: a lever 106 pivotally mounted at 107 is provided with a pawl 108 pivotally mounted on one end and biased in a counterclockwise direction by a spring 108' (Fig. 1). The pawl is provided with two projections having a V-shaped relation to each other and the lower end of the lever 96 terminates within the notch formed by the two projections. One of the projections extends towards and resides in the plane of a circular rack 109 which is slidably mounted on a wheel 110 fixed to a shaft 111 which in turn has a gear fixed thereto which meshes with the gear 21 and is driven thereby. When the lever 106 is caused to rock clockwise one of the projections on the pawl 108 is engaged by one of the teeth 112 of the rack which causes the pawl 108 to be rocked clockwise. This action of the pawl causes the other projection to strike the lower end of the member 96 to move it counterclockwise. 35 40 45 50

55 The operation of the zoning mechanism for selecting the time that printing is effected, which includes the rack 109 and associated parts, will be described later.

Storing mechanism

As it takes two card cycles of the machine from the time that the cards are read by the brushes 49 to the time the card is positioned for receiving a printed record of the data read, it is necessary to provide a means for storing the readings made by the brushes until the card has reached printing position at which time these readings may be utilized to control a printing operation. Such storage mechanism is shown in Fig. 2 in which two cams 41 and 42 make one revolution for every two card cycles as previously explained. The box cam 42 has associated therewith a cam follower 113 which is connected by means of a connecting rod 114 to a crank 115 fixed to a shaft 116 which extends across the mechanism and is journaled in the side supporting plates 117 of the storage mechanism. A gear 118 is fixed to said shaft and meshes with two gears 119 and 120 which are

fixed to the shafts 121 and 122 respectively which are likewise journaled in the side supporting plates 117. A series of collars are keyed to the shafts 121 and 122 on which are frictionally mounted ratchet disks 123 and 124. The sectional view in Fig. 6 clearly shows this construction in which the collars 125 are fixed to the shaft 122 by the key 126 and the disk 124 is frictionally held against the collar by a spring 127. The disks 123 and 124 are provided with twelve ratchet teeth corresponding to the twelve index point positions in a card column (Fig. 4). Projections 128 and 129 integral with the ratchet disks cooperates with limit stops 130 and 131 respectively to limit their distance of rotation in one direction. Outwardly turned lips 132 and 133 extend from the periphery of the disks 123 and 124 (Figs. 2 and 6). Spring contacts 134 and 135 are mounted on a bracket 136 and are located in the plane of the orbit of rotation of lips 132 and 133 respectively. One blade of the contacts is provided with a piece of insulation which rests on the lip of the ratchet disk when said disk is in its home position as shown by the ratchet wheel 123, lip 132 and contact 134 (Fig. 2) in which these parts are shown in their home position. The contacts 134 and 135 are held in closed position when their respective cooperating disks are in their home position. Associated with the ratchet disks 123 are pawls 137 and 138 which are adapted to engage the teeth in the ratchet disks to halt their rotation against the friction drive.

The action of the box cam 42 as it rotates is to oscillate the gear 118 back and forth, thus oscillating the ratchet disks back and forth turning them in one direction during one card cycle and in the reverse direction during the succeeding card cycle. It can be readily seen from the drawing (Fig. 2) that the pawl 137 is adapted to engage the teeth of disk 123 to stop it only when it rotates in counterclockwise direction and the pawl 138 is adapted to engage the teeth in disk 124 only when said disk rotates clockwise. Thus one disk may be stopped during one card cycle and the other disk during the succeeding cycle.

The pawl 137 is fastened to an insulated member 139 which is mounted on a lever 140 pivotally mounted at 141 and the pawl 138 is similarly mounted on an insulated member 142 fixed to a lever 143 pivotally mounted at 144. The insulated members 139 and 142 bear against contacts 145 and 146 respectively so that a movement of the lever 140 clockwise causes contact 145 to close and the movement of lever 143 counterclockwise causes contact 146 to close. Levers 140 and 143 are biased clockwise and counterclockwise respectively by springs 147 and 148 respectively.

A latch member 149 pivotally mounted at 150 and biased clockwise by spring 151 engages levers 140 and 143 to normally hold them in their home position. The upper end of latch member 149 has an extension engaging lever 140 and the lower end is hook-shaped to engage a hook-shaped end of lever 143. Lever 149 is connected by a link 155 to the armature 152 pivotally mounted at 153 and operated by a magnet 154. When the magnet is energized, the latch member 149 is rocked counterclockwise to unlatch levers 140 and 143. In the position shown in Fig. 2, the latch member 149 has been moved to unlatching position freeing levers 140 and 143 to be moved by the springs 147 and 148 respectively. The lever 143 has moved counter-clockwise and dropped the pawl 138 into one of the teeth on ratchet disk 124 at the same

time closing contacts 145 whereas the pawl 137 is resting on the outside periphery of the disk 123 preventing movement of lever 140. If the release of the latch member 149 had occurred earlier in that cycle, the pawl 137 would drop into the notches on the disk 123 as it rotated clockwise thus causing contacts 145 to open and close rapidly. Other cam contacts in series with contacts 145, which will be described later, are at this time opened, however, which will prevent any disturbances in the circuit due to this rapid opening and closing of contact 145.

Bails 157 and 158 pivotally mounted at 159 and 160 are connected by links 161 and 162 to cam followers 163 and 164 respectively. These cam followers engage the cam 41 at points exactly 180° apart. The cam 41 is provided with two bumps 165 situated 180° apart so that as the cam rotates, the two bumps will engage the two cam followers simultaneously, thus causing the bails 157 and 158 to be rocked simultaneously. These bails traverse all of the series of levers 140 and 143 to relatch them at the end of each card or machine cycle.

The number of teeth on the ratchet disks 123 and 124 correspond to the number of index point positions in a column of the card (Fig. 4) and as the index point positions pass under the brush 49 the teeth pass in synchronism with the passage of these index point positions by the ends of the pawls 137 and 138 so that when the brush 49 encounters a perforation in the card at some index point position it creates a circuit through the magnet 154 to cause the pawl 137 or 138 as the case may be to engage that particular tooth in the disk corresponding to that index point position.

Zoning mechanism

The combinational perforations for the cards preferred is shown in Fig. 7. The one to nine positions represent the corresponding point positions and are therefore represented by a single hole in their respective positions. The characters "#", "@," and "%" are taken care of by special plugging in the machine and printing of these characters is effected only if the machine is set up for it when the machine is using numerical characters requiring no zoning. The selector for controlling the printing operation comprises the circular rack 109 (Fig. 1) previously referred to, its carrier 110 and associated parts for moving the ratchet relative to the carrier. As the circular rack is rotated past the end of the projection on the pawl 108 the type wheel 51 is also being rotated and their relative speeds of rotation are such that four type characters on the printing wheel pass through printing position during the time that the selector wheel moves a distance between two teeth 112 relative to the projection on pawl 108. It is obvious then that the relative time at which this projection hits the tooth 112 determines which one of the four type characters is going to be in printing position to record on the record receiving medium. For this reason the circular rack 109 is movable relative to the wheel 110 and this movement is accomplished by momentarily arresting the rotation of the rack 109 while the wheel 110 continues to rotate. The rack 109 is arrested by the engagement of a stud bar 170 integral with the rack by a stepped arm 171 which is moved into the orbit of rotation of the stud bar 170 at the proper time. The amount of displacement of the rack 109 is dependent on which one of the three notches is engaged, which

in turn is dependent on the position of the stepped arm 171. Integral with the arm 171 and extending therefrom is an arm 172. These arms forming a single member are pivoted at 173 and the arm 172 is provided with three notches 174 which correspond to the "0," "11" and "12" index point positions on the card. The arm 172 is resiliently connected to a bail 175 which oscillates back and forth in synchronism with the feeding of the cards so that the three notches 174 pass the projection of a pawl 176 adjacent thereto synchronously with the passage of the index point positions "0," "11" and "12" of the card under the sensing brush 49. The arm 171-172 is moving in a counterclockwise direction at this time. A general description of this structure is being given at this time as a more detailed description as well as more detailed drawings are already disclosed in my United States Patent No. 2,036,-016, dated March 31, 1936, in Fig. 3 of which the teeth 112 of the circular rack 109 in this application correspond to notches 98 of the rack 86 in the above mentioned patent, and those members referred to by reference numerals 170, 171, 172, 173, 174, 175, 176, 177 in this application correspond respectively to the members referred to in Fig. 3 of my above mentioned patents by reference numerals 95, 94, 87, 85, 93, 84, 82, and 101.

The engagement of a notch 174 by the pawl 176 is determined by a perforation appearing in either the "0," "11" or "12" index point positions of the card. If such a perforation does exist, a circuit is completed through a magnet 178 when the perforation passes under the brush 49 energizing said magnet to attract its armature 179 to withdraw the latch member 180 from engagement with pawl 176 so that it engages the notch 174 corresponding to the index point position perforated and thus arrest the movement of the arm 171 in a position so that the corresponding step on said arm will engage the stud 170 to shift the position of rack 109 relative to the wheel 110. The shifted position of the rack is maintained by a pawl 177 mounted on the wheel 110 which engages notches in the rack 112. The pawl 177 is restored by the bail 181 operated by the cam follower 182 cooperating with a cam on the shaft 111. This bail corresponds to the bail 100 in the above mentioned patent and the bail 183 for restoring the pawl 176 corresponds to the bail 105 in said patent.

As previously mentioned, printing is effected by dropping the lower projection of the pawl 108 into the orbit of rotation of the teeth 112 to turn the pawl clockwise and so effect the member 96. The control for dropping this pawl 108 is the magnet 184 which is connected by means of a link 185 connected from its associated armature 186 to a latching member 187. This latching member is provided with a shoulder 188 which holds the pawl carrier 106 so that the pawl 108 is clear of the rack 109. When the magnet 184 is energized it attracts its armature 186 and by means of the link 185 moves the latch member 187 counterclockwise about its pivot 189 to release the pawl carrier 106 which rotates clockwise under the biasing action of the spring 190 and so places the pawl 108 into the path of rotation of the teeth 112 to effect a printing operation. The latching member 187 is biased in a clockwise direction by a spring 191. A bail 192 restores the pawl carrier 106 to its latched position after printing is effected. This bail corresponds to the bail 131 (Fig. 2) of my previously mentioned patent which acts upon the pawl 75

carrier 112 corresponding with pawl carrier 106 just described.

The contact 193 shown in Fig. 1 is a card lever contact operated by a lever extending into the path of the cards which is kept closed as long as cards are being fed. This is old in the art and requires no further illustration. Such contact and lever, for example, is shown in the United States patent to E. A. Ford, No. 1,684,389, previously referred to and is designated therein by reference numerals 156 and 157 in Figs. 4 and 11 of that patent.

The zero suppression mechanism generally shown at 195 (Fig. 1) is old and plays no part in the present invention and it is therefore believed no description is necessary. An identical mechanism is shown in my United States Patent No. 2,030,427 in Fig. 7 of that patent.

Operation

Turning now to the wiring diagram in Fig. 8, the manner in which the structure just described cooperates through the medium of the circuits in the machine will be explained. A switch 195 when closed connects a suitable source of power to the machine. To start the machine in operation, the start key is pressed, closing contacts 196 which starts the motor M operating through a circuit starting from one side of the supply line 197, through contacts 196, relay coil 198, motor M and back to the other side of the supply line 199. If record cards are in the magazine, they will start to feed through the machine and in the first part of the machine cycle, the leading card will cam the card lever contact 193 closed and said contact will be held closed as long as cards continue to be fed through the machine. When the card lever contact 193 closes, a circuit is established through the card lever relay magnet 200 as follows: from one side of the supply line 197, through wire 201, 202, 203, 204, card lever contact 193, card lever relay coil 200, resistance R, wires 205, 206, 207, 208, 209, to the other side of the supply line 199. The energization of card lever relay magnet 200 causes card lever relay contacts 210 and 211 to close. Motor relay contacts 212 are closed by the magnet 198 when the start key contacts are closed so that the closure of relay contacts 211 will establish a holding circuit through relay magnet 198 and keep the motor M running as long as cards continue to be fed and after the start key contact 196 is opened. This holding circuit is from one side of the supply line 197, through wire 201, stop contacts 213 (normally closed), relay contacts 211 and 212 (now closed), magnet 198, motor M, to the other side of the supply line 199. When the card magazine is emptied and no further cards are fed, card lever contact 193 will open, deenergizing relay 200 and therefore opening contact 211 which will break the holding circuit to stop the motor. If it is desired to stop the machine while cards are still feeding, the stop key may be depressed to open contacts 213 which will likewise break the holding circuit.

The card lever, diagrammatically indicated at 220 (Fig. 8) is of sufficient length to bridge from the following edge of the leading card to the leading edge of the following card so that it does not open at the space between cards. When the last card leaves the card lever contacts 193 will open but that would normally stop the machine before the last card has passed the sensing brushes 49. To avoid this a cam contact 221 is

provided which is operated by a cam 222 geared to the driving mechanism and so timed as to close the contact 221 just prior to the following edge of each card leaving the card lever and opening after the card has fed far enough to clear the sensing brushes. Contacts 221 bridge the contacts 213 and 211 so that the motor M will continue to run after contacts 211 have opened sufficient to feed the last card past the brushes, and also if the stop contacts are opened it will continue to operate the machine until the card then being fed under the sensing brushes has been completely read.

The foregoing fully describes the motor circuit and its control.

When the card lever relay contact 210 is closed, the circuit from the power supply line 197 is extended to the brush 214 which wipes on the contact roll 27. The cards are fed between the contact roll 27 and the brush 49. A plug wire 215 is connected between plug sockets 216 and 217 to further extend the circuit through the sensing magnets 154 and through the cam contacts 218 to the other side of the power supply line. The cam contacts 218 act as circuit breakers to break the circuit from the brushes and it is operated by a cam 219 which causes the contacts to open and close at each index point position of the card as it passes under the brush 49 and holds the contact 218 open during the gap between the cards when the brush 49 would be resting directly on the contact roll. Let it be assumed for the purpose of explanation that the card being fed has one column perforated to represent the letter "S." While the description throughout is confined to a single type wheel, it will be understood that a plurality of type wheels are mounted side by side on the shaft 155 and that the same mechanism as described cooperates with each type wheel. There may be as many type wheels and associated controlling and printing mechanisms as there are columns in the card and they all operate in the same manner as described herewith for a single type wheel unit. For the letter "S" there would appear in the selected column a perforation at the "3" index point position and another perforation at the "12" index point position. As this column passes under the brush 49 the teeth of the disk 123 (Fig. 2) will be passing the end of pawl 137 in synchronism with the index point positions of the card as they pass the brush. As the bottom edge of the card (Fig. 4) leads, the seventh index point position will be the "3" index point. Therefore, when the brush encounters a perforation at this point it will make a contact with the roll 27 closing a circuit through the sensing magnet 154 which will allow the pawl 137 to engage the seventh tooth on the disk 123 (Fig. 2). When the disk 123 starts to move counterclockwise the contact 134 opens. Obviously, it will take as much time in the following cycle for the disk 123 to return from its arrested position to close contact 134 as it has taken from the time it opened said contact to arrive at its arrested position. This should be kept in mind for the later explanation of the final printing operation. The circuit which is closed through the magnet 154 is as follows: from one side of the supply line 197, through wires 201, 202, 203, 204, contacts 210, brush 214, contact roll 27, brush 49, plug socket 216, plug wire 215, plug socket 217, sensing magnet 154, contacts 218, wires 206, 207, 208, 209 to the other side of the power supply 199.

When the pawl 137 drops into the tooth it closes contacts 145 to connect the zoning magnet 178 in circuit. Cam contact 228 is controlled by the cam 223 and only closes as the "0," "11" and "12" index point positions pass the brush 49 so that the magnet 178 is energized when the perforation at the "12" index point position passes the brush 49 (according to the example set forth) to select the last notch 174 (Fig. 1) 5 corresponding to said perforation. With the passage of the last index holes "12" past the reading brush 49 the reading of the card is completed and reading is stored in the ratchet disk 123 (Fig. 2) and the circular rack 109 is displaced relative to wheel 110 and held by the pawl 177 (Fig. 1). During the next cycle the readings of the following card are being set up on the ratchet disk 124 and contacts 146 are connected in circuit with magnet 178 in the same 10 manner as just described. During this second cycle, however, the ratchet disk 123 reverses its direction of rotation and returns in timed relation to the rotation of the type wheel 51 and the circular rack 112 so that when it returns to its 15 home position to close the contacts 134 the proper tooth 112 in the circular rack 109 will be in a position to act upon the pawl 108 (Fig. 1). When the contacts 134 close, a circuit is set up to the printing magnet 184 as follows: from one 20 side of the supply line 197, through wires 201, 202, 203, cam contact 224, contacts 134, plug wire 225, printing magnet 184, circuit breaker 226, wires 208 and 209 to the other side of the power 25 supply. The energization of printing magnet 184 releases the pawl carrier 106 and printing is effected as previously explained. The cam contacts 224 and 227 are alternately opened and closed during alternate machine cycles to connect the contacts 134 in circuit during one cycle 30 and the contacts 135 during alternate cycles.

It is sometimes desirable to use the characters "#," "@," or "%." In such cases, however, a 35 definite column in the card is allocated to this use and it will therefore always print in the same relative position on the card. This is accomplished by plugging up the brush coinciding with that card column directly to zoning magnet. As, for example, the brush 49' may be connected 40 up by a plug wire 230 directly to the zoning magnet 178'. The brush 49' would be the brush corresponding to the column on the card that designated these characters. As there would be a 45 perforation in only one of the three positions "0," "11," or "12," and as the circuit breaker 222 only closed at those positions the zoning magnet 178' would be energized directly from the sensing brushes.

The magnet 90 which controls the ejection of the card over the gate 52 is in circuit with a 50 cam operated contact 231 which is controlled by the cam 232 to close the contact after each printing operation to eject the card.

As previously stated, the bracket 62 (Fig. 1) carrying the card gate and ejection assembly is 55 slideable along the machine and is located by the engagement of the bolt 92 with holes 71a, 71b, 71c, etc., and as also previously stated a suitable sliding contact having one member fixed to the frame and one to the bracket 62 is provided so that a contact is made between the contact members only when the frame 62 is located by the holes 71b and 71c for the purpose of actuating the deflector 80 (Fig. 3) for the reasons previously set forth. Such a sliding 60 contact is diagrammatically shown at 233 (Fig. 75

8) and it is connected in series with a cam operated contact 234 which is controlled by the cam 235 to close said contact to energize magnet 90 to operate the deflector 80 just after the leading edge of the card passes said deflector.

While I have shown and described and pointed out the fundamental novel features of the invention as applied to a single modification it will be understood that various omissions and substitutions and changes in the form and details of the device illustrated and in its operation may be made by those skilled in the art without departing from the spirit of the invention. I intend to be limited therefore by the scope of the following claims.

What is claimed is:

1. In a card controlled printing machine, a plurality of type elements, a single sensing station, means for feeding cards past said sensing station, means for continuously moving said type elements, a printing hammer, means for impelling said printing hammer against said elements to effect printing thereby, storing means controlled by said sensing station for storing data read from said card when passing said station, means controlled by said storing means to render said impelling means operative and means in synchronism with said moving type elements and controlled by said storing means to control the time of operation of said impelling means to effect printing while said type elements are in motion.

2. In a printing machine controlled by cards having data indications thereon, a plurality of type elements, means for continuously moving said type elements, a single sensing station for reading the data indications on said cards, means for feeding said cards to said station, a printing hammer, means to impel said hammer against one of said type elements to effect printing thereby, storing means for receiving and storing the data read by said sensing station from the data indications, and means controlled by said storing means to control the operation of said impelling means to effect printing of the data stored therein while said elements are in motion.

3. A printing machine controlled by record cards having data representations perforated therein, including a single sensing station for reading said representations, means for feeding a plurality of record cards successively past said sensing station, a plurality of continuously moving type elements, means operable by said feeding means for moving said record cards from said sensing station to a position adjacent said type elements, a printing hammer, means to impel said printing hammer against one of said type elements to effect printing thereby, storing means controlled by said sensing station for receiving and storing data as read thereby from the data representations on said record cards, and means controlled by said storing means to control the operation of said impelling means to effect a printing operation on said record cards when positioned adjacent said type elements.
4. The invention as set forth in claim 3 in which adjustable means are provided for arresting the motion of the card when adjacent said type elements and in selected positions relative to said type elements whereby printing may be effected at selected locations on the record card.
5. A printing machine controlled by record cards having data representations perforated thereon, including a sensing station for reading said representations, means for feeding a plurality of record cards successively past said station, a plurality of continuously moving type elements, means operable by said feeding means for moving said record cards from said sensing station to a position adjacent said moving type elements, a printing hammer, means to impel said printing hammer against one of said type elements to effect printing thereby, storing means for receiving and retaining data read from a record card by the sensing station, and means controlled by said storing means to control the operation of said impelling means to effect printing of the data retained in said storing means on said card while said storing mechanism is receiving and retaining data read by the sensing station from the next succeeding card.

EUGEN BUHLER.
